UNITED STATES PATENT OFFICE

ROSS SHIELDS, OF IPAVA, ILLINOIS

VANITY CASE

Application filed July 27, 1931. Serial No. 553,434.

This invention relates to a vanity case and has for its primary object to provide, in a manner as hereinafter set forth, a device of this character embodying a novel construction, combination and arrangement whereby various accessories, such as a lip stick, powder box, powder puff and rouge may be carried in a manner to permit the same to be conveniently used when desired.

10 Other objects of the invention are to provide a vanity case of the character described having a novel and attractive shape and appearance, which may be conveniently carried, which will be simple in construction, strong, durable and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

25 Figure 1 is a view in side elevation of a vanity case in accordance with this invention.

Figure 2 is a view in vertical longitudinal section through the vanity case.

30 Referring now to the drawings in detail, it will be seen that the invention comprises an elongated, longitudinally and laterally curved tapered case 1 of any suitable material and which may have its exterior attractively ornamented in any suitable manner, as at 2. Eyes 3 are anchored in the upper side of the case 1 adjacent the ends thereof and constitute means for connecting the ends of a carrying chain 4 to said case. The case 1 is open at its ends, the small end of said case having mounted therein and adapted to project therefrom a lipstick 5. A closure 6 is provided for the large end of the case 1.

The enlarged end portion of the case 1 is counterbored in a manner to provide an internal annular shoulder 7 upon which an appropriately shaped powder box 8 seats.

The reference numeral 9 designates a powder puff which may be carried in the case adjacent the powder box 8 while a supply of

rouge is designated by the reference numeral 11. Of course, any desired articles may be carried in the case.

The novel shape of the case 1 materially facilitates the use of the lipstick 5, the case functioning as a handle for the lipstick, as will be apparent. In addition, the novel and attractive configuration of the case 1 adapt said case to be conveniently carried through the medium of the chain 4. Also, the novel shape of the case lends considerable strength thereof, as will also be apparent.

It is believed that the many advantages of a vanity case in accordance with this invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A vanity case comprising an elongated, longitudinally curved receptacle for the reception of toilet articles, and a carrying chain connected, at its ends, to the end portions of said receptacle on the inwardly curved side of said receptacle.

2. A vanity case comprising a tubular receptacle, said receptacle being open at its ends and tapering from end to end, a lipstick mounted in the small end portion of the receptacle and projecting therefrom, said receptacle constituting a handle for the lipstick, and a closure on the large end of the receptacle.

3. A vanity case comprising a tubular receptacle, said receptacle being open at its ends and tapering from end to end, a lipstick mounted in the small end portion of the receptacle and projecting therefrom, a closure in the large end of the receptacle, the large end portion of the receptacle being counterbored to provide an internal shoulder, and a powder box disposed in the receptacle and seated against the shoulder.

In testimony whereof I affix my signature.

ROSS SHIELDS.
